The ornamental design for a thermal pack, as substantially shown and described.

DESCRIPTION

FIG. 1 is a perspective view of a thermal pack showing the new design;

FIG. 2 is a front plan view thereof;

FIG. 3 is a rear plan view thereof;

FIG. 4 is a top elevation view thereof;

FIG. 5 is a bottom elevation view thereof;

FIG. 6 is a left-side elevation view thereof; and,

FIG. 7 is a right-side elevation view thereof.

The spheres or beads illustrated in the drawings are drawn so as to appear as transparent or semi-transparent. The baffle illustrated is formed of two transparent pack walls, sealed together to form a thin, flat, planar surface illustrated in the drawings. The shading lines indicate the clear or transparent nature of the baffle. Structure illustrated in broken lines is not otherwise part of the claimed design.
